UNITED STATES PATENT OFFICE.

HENRY BERRY AND KEYES A. HATHAWAY, OF BIRMINGHAM, CONNECTICUT.

DESIGN FOR A CASTER.

SPECIFICATION forming part of Design No. 14,523, dated December 25, 1868.

Application filed November 7, 1868. Term of patent 7 years.

To all whom it may concern:

Be it known that we, HENRY BERRY and KEYES A. HATHAWAY, citizens of the United States, residing at Birmingham, in the county of New Haven and State of Connecticut, have invented certain new and useful Improvements in Designs for Casters; and we do declare the following to be a full, clear, and exact description of the invention, such as will enable others skilled in the art to which it applies to make and use the same, reference being had to the accompanying drawing, and to letters or figures of reference marked thereon, which form a part of this specification.

15 The figure of the drawing is a representation of a perspective view of the caster.

The drawing represents a caster or cruet-

stand, the exposed surface of the body portion being ornamented in conventional imitation of alligator-skin, as at *a*, this being the 20 essential feature of the design.

Having described this design, what we claim is—

The design for a caster or cruet-stand, having the surface ornamentation of the body 25 portion in representation of alligator-skin, as shown and described.

In testimony whereof we affix our signatures in presence of two witnesses.

HENRY BERRY.

KEYES A. HATHAWAY.
